COMBINATION SHOWER AND DOUCHE
Florence B. Zacks, 78 E. Chestnut St., Columbus, Ohio
Filed Aug. 16, 1961, Ser. No. 131,764
7 Claims. (Cl. 128—227)

This invention relates to douches or syringes, either rectal or vaginal, and more particularly to such devices as are capable of use in connection with a constant supply of water.

Syringes and douching devices in general use are of two types, both intended to be used over a toilet bowl or hopper, and both are quite uncomfortable, untidy, and unsatisfactory. First, there is the so-called fountain syringe comprising a generally flat enema bag provided with a douche nozzle attachment.

In the use of this device, the usual pinch-cock is closed upon the discharge tube, the bag is filled with water and hung on a wall hook in an elevated position. The slight pressure head afforded by the elevation of the bag, and the usual dimensions of the tubing yield at best only a slight flow or trickle of water. The other device is the bulb hand syringe comprising a rubber bulb and attached douche nozzle. This appliance is filled at the wash-basin and used over the toilet by hand pressure on the bulb. This process is also untidy and generally unsatisfactory.

Other means for the purpose have been suggested but have involved elaborate plumbing installations, and as a consequence have not come into general use. Some of such devices include the provision of tubing connected to the faucets of the wash-basin or bath tub, but the direct pressure of the house water supply is not easily controllable and may inadvertently be applied at a dangerously high degree.

The present invention, therefore, has for its general object the provision of a novel and improved douche device which is much more satisfactory than those heretofore employed, and which is tidier and more cleanly and orderly in use. The outstanding feature of novelty of the invention is the possibility of the user effecting a thorough cleansing douche at the same time she is taking a shower, the process being accomplished with a continual supply of water but not under the hazardous full pressure of the water system.

The invention, in its preferred embodiments, contemplates the provision of a novel douche bag which is adapted to be used in conjunction with the usual rose or spray nozzle of the shower-bath equipment, whether installed above a bathtub or in a shower stall. The bag is of suitable waterproof fabric or other material, such as plastic, rubber, rubberized cloth or the like, and is provided with a wide, open, upwardly directed mouth, about a portion of the periphery of which is provided a supporting web or sheet which may be of the same or similar waterproof material as the bag itself. A conventional discharge tube, terminating in a douche nozzle, is suitably connected with an opening in the lower portion of the bag.

The supporting web or sheet is preferably tapered upwardly and its restricted upper or apex end is provided with means for suitably detachably securing it to the neck of the shower nozzle, in such a manner that the shower nozzle or rose is disposed a short distance above the mouth of the bag proper so as to forcibly discharge a rather strong spray of water into the bag but so that the bag may readily overflow and preferably so that some portions of the shower water avoid the bag and descend upon the bather in the usual way.

Other objects and features of novelty will be apparent from the following specification when read in connection with the accompanying drawings in which certain embodi-

2

ments of the invention are illustrated by way of example. In the drawings:

FIGURE 1 is a somewhat diagrammatic view, mainly in elevation, of an installation embodying the principles of the invention, portions thereof being shown in vertical section;

FIGURE 2 is a view in front elevation of a bag and supporting means in flat empty condition;

FIGURE 3 is a view in transverse section taken on line 3—3 of FIGURE 2;

FIGURE 4 is a fragmentary view in front elevation showing a modified form of supporting or suspension means;

FIGURE 5 is a view similar to FIGURE 3 being a transverse section along line 5—5 of FIGURE 4;

FIGURE 6 is a fragmentary view in front elevation of the upper end of a supporting web showing a modification in the attaching means; and

FIGURE 7 is a view in perspective of the upper end of a supporting web illustrating another embodiment of the attaching means.

FIGURE 1, although a somewhat diagrammatic showing and not necessarily to actual scale, depicts one example of the practice of the invention. The wall of the bathroom is indicated at 10 and extending therefrom is the plumbing fixture 11 which terminates in a shower spray rose 12 which is usually inclined downwardly at an angle to the vertical.

Secured about the neck portion 13 of the rose 12 and suspended therefrom is a douche bag device indicated generally by the reference numeral 15, and comprising the bag 16 made of flexible material of a preferably waterproof nature such as rubber, plastic, rubberized fabric, or the like. This bag is attached to the neck 13 of the spray nozzle by means of the webbing 18, the details of which will be described presently.

Extending from the bottom of the bag by means of a suitable connection of known type is the rubber or plastic tubing 20 and secured to the remote end of the tubing is the douche nozzle 21. Flow through the tubing 20 is readily controllable by a conventional pinch cock 22.

One of the more unique features of the present invention resides in the nature, construction, and manipulation of the supporting web or sheet 18 by which the bag is suspended from the neck of the shower rose. In one embodiment of the invention (see FIGURES 1, 2 and 3) the web 18 is of a tapering or roughly triangular configuration, the edge of the web forming the base of the triangle being secured as at 24 to the upper edge of the mouth of the bag 16. In this embodiment, the length of the base along the line 24 is less than one-half the width of the flattened bag and approximately one-third of the circumference of the mouth of the bag.

The upper or blunt apex end of the web 18 may be provided with a heading or folded-over portion as at 25 adapted to be wrapped at least part way around the neck 13 of the shower nozzle, and providing a tubular passageway for the drawstring 26.

The upper portion 25 of the web 18 is applied to the neck 13 of the shower rose 12 as indicated in FIGURE 1, the drawstring 26 being tied in a suitable manner to support the whole device in the position shown. The lower edge of the webbing 18 being of less extent than the width of the bag, it does not interfere with the opening of the bag to a rather full extent by the reception of the water from the shower rose.

The main spray 30 from the shower rose is directed somewhat at an angle so that preferably at least half of the water delivered is directed into the bag. The bag fills with water as at 31 up to the approximate level of its mouth and discharges through the tubing 20, when

the pinch cock 22 is open and furnishes a spray at the proper pressure to the douche nozzle 21.

A certain proportion of the shower spray 30 passes beyond the mouth of the bag and descends upon the subject as a partial shower spray indicated at 35. Thus, the user may employ the douche at the same time she is taking a shower.

In FIGURES 4 and 5 of the drawings there is illustrated a modification of the device in which the lower edge junction of the suspension web 18' extends around the margin of the mouth of the bag 16' more than half way. Otherwise the features are the same as those shown in the disclosure of the earlier embodiment. In this second embodiment, the supporting web 18' must take a more arcuate form and although it may provide a somewhat sturdier support for the bag, it may have the effect of limiting the amount of the residual shower portion 35 of the water supply. Both of these embodiments are operative and it is a matter of personal preference as to whether one has an advantage over the other or not.

Although in the two embodiments already described, the attaching means comprises the drawstring 26, other means of securing the suspension webbing to the neck of the shower rose may be employed in either case. For example, in FIGURE 6 of the drawings the upper portion 25' of the webbing 18 or 18' may take the form of a reinforced fabric strip having mating elements 36 and 37 of a snap fastener device secured to opposite ends thereof whereby the portion 25' may be wrapped around the neck 13 of the shower fixture and the ends secured together in overlapping relationship by means of the snap fastener combination 36, 37.

A still further modification of the attaching means is illustrated in FIGURE 7 of the drawings where the web 18 or 18' is provided with an upper tubular reinforcing collar portion 25" through which extends the spring clip 26', the ends of which may protrude from the portion 25" and be turned outwardly so that they can be readily snapped in position around the neck 13 of the shower rose.

It will be understood that various changes and modifications may be made in the embodiment illustrated and described herein without departing from the scope of the invention as defined by the following claims.

Having thus described the invention, what is claimed as new and desired to be secured by Letters Patent is:

1. A shower douche device comprising, in combination, a supporting structure, a shower bath spray rose having a neck extending from said supporting structure and serving to suspend said rose to extend and to face in a generally downward direction, and means for supplying said rose with water under normal water supply pressure, and a douche bag of somewhat flexible material and provided with a discharge tube extending from the bottom thereof and a douche nozzle carried by the remote end of said discharge tube, said bag having a wide upwardly-opening mouth constituting the greater portion of the upper end of the bag and being of an area considerably greater than that of the shower rose, and means for suspending said bag with its mouth positioned generally beneath said rose and spaced somewhat therefrom, said suspending means having a lower end

secured to the upper end of the bag and provided with means at its upper end for attaching said suspending means to the neck of the shower bath rose, the vertical length of said suspending means being somewhat greater than the vertical height of the rose from its lower end to its neck and thus sufficient to position the wide upwardly-opening mouth of the bag at a level below that of the rose, whereby the entire flow from the rose is not confined by the bag and the pressure head of the water in the bag is not increased above that of the gravity of the contents.

2. The shower douche device as set forth in claim 1 in which said suspending means comprises a web of flexible material of quadrilateral contour, a lower edge thereof being secured throughout its length to a portion of the peripheral edge of the mouth of the bag, and the attaching means comprising a strip adapted to surround the neck of said rose.

3. An article of manufacture, a douche bag device adapted for suspension from the spray nozzle or rose of a shower bath installation, said device comprising a bag of somewhat flexible material and provided with a discharge tube extending from the bottom thereof and a douche nozzle carried by the remote end of said discharge tube, said bag having a wide upwardly-opening mouth constituting the greater portion of the upper end of the bag and being of an area considerably greater than that of any shower rose to which it may be attached, suspension means for said bag comprising a web of material of quadrilateral configuration and having a lower edge secured throughout its length to a portion of the peripheral edge of the mouth of the bag, an upper edge of said web being shorter than said lower edge, and strip means positioned along said upper edge and adapted to surround the neck of a shower rose for suspending said bag therefrom.

4. The douche bag device as set forth in claim 3 in which the length of the lower edge of said suspending web is less than one-half of the periphery of the mouth of the bag.

5. The douche bag device as set forth in claim 3 in which the length of the lower edge of said suspending web is more than one-half of the periphery of the mouth of the bag.

6. The douche bag device as set forth in claim 3 in which said attaching strip means comprises a strand having ends adapted to be secured together when the device is applied to the neck of the rose.

7. The douche bag device as set forth in claim 3 in which said attaching strip means comprises a narrow spring clip.
